UNITED STATES PATENT OFFICE.

LEWIS L. NETTLETON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 22, 1926. Serial No. 143,378.

My invention relates to railway traffic controlling apparatus, and particularly to apparatus of the type involving train-carried governing mechanism controlled inductively by current flowing in the track rails.

One feature of my invention is the provision of means for giving three indications on the train with a single trackway circuit for each section and a single train-carried receiver.

I will describe one form of apparatus embodying my invention, and will then point out the novel features thereof in claims.

In the accompanying drawing, Fig. 1 is a diagrammatic view showing one form of apparatus embodying my invention. Fig. 2 is a group of curves illustrating the operation of the apparatus shown in Fig. 1. Fig. 3 is a curve showing the characteristics of the electron tubes forming part of the apparatus shown in Fig. 1.

Referring first to Fig. 1, the reference characters 1 and 1^a designate the track rails of a stretch of railway track along which traffic normally moves in the direction indicated by the arrow. These rails are divided by insulated joints 2 into a plurality of sections of which only two complete sections A—B and B—C are shown in the drawing. As here shown, each section is provided with a signal S located at the entrance end of the section and arranged to indicate proceed, caution or stop. Inasmuch as the control of these signals has nothing to do with my present invention I have omitted the controlling apparatus from the drawing to simplify the disclosure. Furthermore, the signals may be omitted, if desired.

Each section is provided with a source of direct current, which, as here shown, is a battery D, and this battery is connected with the track rails adjacent the exit end of the section through a pole-changer P which is operated by the signal S for the next section in advance in such manner that the pole-changer is in its normal position when the signal indicates proceed or caution, and in its reverse position when the signal indicates stop. Interposed between each pole-changer P and one track rail is an interrupter I, which, in the form here shown, is a commutator constantly operated by a motor M which in turn is energized from the adjacent battery D. The commutator I

is preferably so arranged that the period during which current is supplied to the track rails is considerably greater than the period of interruption. The interrupter I is shunted by a condenser 3, and a reactor 4 is interposed between the interrupter I and the track rail 1^a.

Located to the right of point C, is a train or vehicle represented by a pair of wheels and an axle V. Located in front of the forward wheels and axle of this train is a core 5 transversely disposed above the track rail 1 and a core 5^a transversely disposed above the track rail 1^a. The core 5 carries a coil 6, and the core 5^a carries a coil 6^a, which coils are connected in series in a receiving circuit L in such manner that the voltages created in the two coils by current flowing in opposite directions in the track rails at a given instant are additive. It will be seen, therefore, that the two coils 6 and 6^a constitute a winding which receives voltage inductively from the track rails. The vehicle V also carries a normal electron tube E¹ and a reverse electron tube E², each of which tubes is of the three-element type having a filament, a grid and a plate. The filament of each tube is constantly heated by a battery 12. The grid circuits of the tubes E¹ and E² are reversely connected with the receiving circuit L, that is, the filament of tube E¹ is connected with the upper terminal of coil 6 and the grid of this tube is connected with the lower terminal of coil 6^a, whereas the filament of tube E² is connected with the lower terminal of coil 6^a and the grid of tube E² is connected with the upper terminal of coil 6. The grid of each tube is maintained negative with respect to the filament of the same tube by a battery 13. Tube E¹ is provided with a plate circuit including a winding 14 of a relay R and a plate battery 10. Tube E² is provided with a plate circuit including a winding 7 of relay R and a plate battery 10. The relay R comprises an armature 9, which is shifted to the right into engagement with fixed contact 9^a when winding 14 is energized, and to the left into engagement with fixed contact 9^b when winding 7 is energized. The relay R may control train governing mechanism of any suitable type, which mechanism, as here shown, is a cab signal S¹, having a high speed lamp 8^H, a medium speed lamp 8^M, and a stop lamp

8s. The circuits for these lamps will be obvious from the drawing, from which it is seen that each lamp is supplied with current from a suitable source the terminals of which are indicated by the reference characters K and O.

The operation of the apparatus shown in Fig. 1, is illustrated by the curves constituting Figs. 2 and 3. In Fig. 2, the curve F illustrates the operation of the interrupter I, and from this curve it will be noted that, as stated hereinbefore, the interrupter is closed for relatively long intervals X, and open for relatively short intervals Y. The current in the track rails is indicated in curve G, the solid lines in this portion of Fig. 2 showing the current when the pole-changer P is in normal position and the dash lines showing the current when the pole-changer is in the reverse position. Due to the reactor 4 and to the inherent reactance of the track rails, the time constant of the track circuit is such that during each period X the current builds up slowly, as indicated at a, while during each period Y the current dies out quickly, as shown by the portion b of the current curve. When the pole-changer P is in the reverse position, the two portions of the current curve are as illustrated by the parts a¹ and b¹. The condenser 3 across the interrupter serves both to reduce sparking at the interrupter contacts and also to increase the steepness of the portions b and b¹ of the current curves. Curve H shows the wave form of the voltage inducted in the receiving circuit L on the train. When the pole-changer is in the normal position, the voltage has a positive peak d which is relatively high, and a negative peak c which is relatively low. When the pole-changer P is in the reverse position, the curve has a negative peak d¹ which is relatively high and a positive peak c¹ which is relatively low. Fig. 3 shows the characteristic curve of each electron tube E¹ and E². From this curve it will be noted that due to the negative bias created by the battery 13, a considerable grid voltage is required to overcome this bias. Tube E¹ is so connected with the receiving circuit that it will respond to the normal voltage, that is, to the voltage indicated by the solid line in curve H of Fig. 2, whereas tube E² is so connected to the receiving circuit that it will respond only to the reverse voltage, that is, to the voltage indicated by the dash line in curve H of Fig. 2. It follows that when pole-changer P is in the normal position, winding 14 of relay R will be energized but winding 7 will be de-energized, whereas when the pole-changer P is in the reverse position, winding 7 will be energized and winding 14 will be de-energized.

It will be seen from the foregoing that I

have provided means for each track section for reversibly applying to the rails of the section a periodic current each wave of which builds up slowly from zero to a maximum and dies away quickly from maximum to zero, and that I have provided means on the train selectively responsive to the relative polarity of such current in the track rails.

As illustrated in Fig. 1, the section immediately to the left of point A is occupied by a second vehicle V^A; so that pole-changer P for section A—B is in the reverse position, whereas pole-changer P for section B—C is in the normal position. It follows that when the vehicle V enters section B—C, relay R will continue to be energized in the normal direction so that the high speed lamp 8^H will continue to be lighted, but that when the vehicle enters section A—B the energization of relay R will be reversed, so that the medium speed lamp 8^M will become lighted. Of course, when the vehicle enters an occupied section or when for any other reason the supply of energy from the track rails is discontinued, armature 9 of relay R will assume its intermediate position wherein the stop lamp 8^S will be lighted.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of railway track, a source of direct current reversibly connected with the rails of said section, means for periodically interrupting the supply of current from said source to the track rails, a train carried circuit receiving energy inductively from the track rails, two electron tubes having their grid circuits reversely connected with said receiving circuit, two coils supplied with energy by the plate circuits of said two tubes respectively, and governing mechanism on the train controlled by said two coils.

2. In combination, a section of railway track, a source of direct current reversibly connected with the rails of said section, means for periodically interrupting the supply of current from said source to the track rails, a train carried circuit receiving energy inductively from the track rails, two electron tubes having their grid circuits reversely connected with said receiving circuit, means for creating a negative bias on the grid of each tube, two coils supplied with energy by the plate circuits of said two tubes respectively and governing mechanism on the train controlled by said two coils.

3. In combination, a section of railway track, a source of direct current connected with the rails of said section, a pole-changer interposed between said source and said rails, an interrupter interposed between said pole-changer and one rail, a train carried circuit receiving energy inductively from the track rails, two electron tubes having their grid circuits reversely connected with said receiving circuit, two coils supplied with energy by the plate circuits of said two tubes respectively, and governing mechanism on the train controlled by said two coils.

4. In combination, a section of railway track, a source of direct current connected with the rails of said section, a pole-changer interposed between said source and said rails, an interrupter interposed between said pole-changer and one rail, a condenser connected in multiple with said interrupter, a train carried circuit receiving energy inductively from the track rails, two electron tubes having their grid circuits reversely connected with said receiving circuit, two coils supplied with energy by the plate circuits of said two tubes respectively, and governing mechanism on the train controlled by said two coils.

5. In combination, a section of railway track, a source of direct current connected with the rails of said section, a pole-changer interposed between said source and said rails, an interrupter interposed between said pole-changer and one rail, a condenser connected in multiple with said interrupter, a train carried circuit receiving energy inductively from the track rails, two electron tubes having their grid circuits reversely connected with said receiving circuit, means for creating a negative bias on the grid of each tube, two coils supplied with energy by the plate circuits of said two tubes respectively, and governing mechanism on the train controlled by said two coils.

6. In combination, a section of railway track, a source of direct current connected with the rails of said section, a pole-changer interposed between said source and said rails, an interrupter interposed between said pole-changer and one rail, a reactor interposed between said pole-changer and one rail, a condenser connected in multiple with said interrupter, a train carried circuit receiving energy inductively from the track way, two electron tubes having their grid circuits reversely connected with said receiving circuit, means for creating a negative bias on the grid of each tube, two coils supplied with energy by the plate circuits of said two tubes respectively, and governing mechanism on the train controlled by said two coils.

7. In combination, a section of railway track, a source of direct current connected with the rails of said section, a pole-changer

interposed between said source and said rails, an interrupter interposed between said pole-changer and one rail, and arranged to be closed for relatively long periods and open for relatively short periods, a condenser connected in multiple with said interrupter, a train carried circuit receiving energy inductively from the track rails, two electron tubes having their grid circuits reversely connected with said receiving circuit, two coils supplied with energy by the plate circuits of said two tubes respectively, and governing mechanism on the train controlled by said two coils.

8. In combination, a section of railway track, a source of direct current reversibly connected with the rails of said section, means for periodically interrupting the supply of current from said source to said rails in such manner that the periods of supply are relatively long and the periods of interruption are relatively short, a train carried circuit receiving energy inductively from the track rails, two electron tubes having their grid circuits reversely connected with said receiving circuit, two coils supplied with energy by the plate circuits of said two tubes respectively, and governing mechanism on the train controlled by said two coils.

9. In combination, a section of railway track, means for reversibly applying to the rails of said section a periodic current each wave of which builds up slowly from zero to maximum and dies away quickly from maximum to zero, a train carried circuit receiving energy inductively from the track rails, two electron tubes having their grid circuits reversely connected with said receiving circuit, two coils supplied with energy by the plate circuits of said two tubes respectively, and governing mechanism on the train controlled by said two coils.

10. In combination, a section of railway track, means for reversibly applying to the rails of said section a periodic current each wave of which builds up slowly from zero to maximum and dies away quickly from maximum to zero, a train carried circuit receiving energy inductively from the track rails, two electron tubes having their grid circuits reversely connected with said receiving circuit, means for creating a negative bias on the grid of each tube, two coils supplied with energy by the plate circuits of said two tubes respectively, and governing mechanism on the train controlled by said two coils.

11. In combination, a section of railway track, means for reversibly applying to the rails of said section a periodic current each wave of which builds up slowly from zero to maximum and dies away quickly from maximum to zero, a train carried winding receiving voltage inductively from said track rails, a normal electron tube having its fila-

- ment connected with one terminal of said winding and its grid connected with the other terminal of said winding, a reverse electron tube having its grid connected with the first terminal of said winding and its filament connected with the second terminal, means for keeping the grid of each tube negative with respect to the filament of the same tube, two coils supplied with energy by the plate circuits of said two tubes respectively, and governing mechanism on the train controlled by said two coils.
12. In combination, a section of railway track, means for supplying to the rails of said section a current which fluctuates periodically and which changes rapidly in a first direction and slowly in a second direction, means for reversing the conditions so that the current changes slowly in the first direction and rapidly in the second direction, and governing mechanism on a train selectively responsive to the two said conditions under which said current is supplied to the rails.
13. In combination, a section of railway track, means for supplying to the rails of said section a current which fluctuates periodically and which changes rapidly in a first direction and slowly in a second direction, means for reversing the conditions so that the current changes slowly in the first direction and rapidly in the second direction, a train carried circuit receiving energy inductively from the track rails, two electron tubes having their grid circuits reversely connected with said receiving circuit, two coils supplied with energy by the plate circuits of said two tubes respectively, and governing mechanism on the train controlled by said two coils.
14. In combination, a section of railway
- track, means for supplying to the rails of said section a current which fluctuates periodically and which changes rapidly in a first direction and slowly in a second direction, means for reversing the conditions so that the current changes slowly in the first direction and rapidly in the second direction, a train carried circuit receiving energy inductively from the track rails, two electron tubes having their grid circuits reversely connected with said receiving circuit, means for creating a negative bias on the grid of each tube, two coils supplied with energy by the plate circuits of said two tubes respectively, and governing mechanism on the train controlled by said two coils.
15. In combination, a section of railway track, means for supplying to the rails of said section a current which fluctuates periodically and which changes rapidly in a first direction and slowly in a second direction, means for reversing the conditions so that the current changes slowly in the first direction and rapidly in the second direction, a train carried winding receiving voltage inductively from said track rails, a normal electron tube having its filament connected with one terminal of said winding and its grid connected with the other terminal of said winding, a reverse electron tube having its grid connected with the first terminal of said winding and its filament connected with the second terminal, means for keeping the grid of each tube negative with respect to the filament of the same tube, two coils supplied with energy by the plate circuits of said two tubes respectively, and governing mechanism on the train controlled by said two coils.

In testimony whereof I affix my signature.

LEWIS L. NETTLETON.
